COSMETIC APPLICATOR

Henry W. Piccot, Tuckahoe, N. Y.

Application November 23, 1935, Serial No. 51,205

11 Claims. (Cl. 132—82)

This invention relates to cosmetic applicators, and particularly has reference to a simple and compact device adapted to automatically apply rouge to the human lips without soiling the fingers, and by means of which quantities of the rouge may be stored and contained in a carrier forming part of the device.

Among the objects of my invention the following may be noted: To provide means by which 10 the rouge can be applied to paper folded and contained within the applicator or an independent receptacle contained within the applicator; to provide means by which one may apply rouge to the lips in a single operation without soiling the 15 fingers, and by which the rouge may be carried in a hand bag, without spilling or soiling the interior of the hand bag or the contents thereof; to provide a cosmetic applicator which is sanitary, 20 clean, contains the proper admixture of oil and coloring matter, and the most delicate perfumes, and which will not leak or run from the applicator, and which when not in use is protected and kept out of contact with the hands of the user, the user's fingers, the handkerchief and 25 other contents of the hand bag; to provide a means by which the entire device can be held in the fingers while the cosmetic is being applied; to provide for the application of rouge by a strip 30 of paper preliminarily folded and subsequently bent over the conformator or holder and which is subsequently thrown away; to provide means for carrying a large quantity of the rouge or cosmetic, and which in order to use the same can be laid over a form provided by the conformator, 35 and by means of which both the lips of the operator can have the proper conformation given to the rouge, applied to the lips quickly and effectively; to provide a carrier for the cosmetic which can be folded within a carton or receptacle 40 independent of the conformator, or which may be folded within the casing or confines of the applicator proper, which applicator can be held locked when not in use, and can be closed upon the strip or rouge carrier, and which latter can 45 be subjected to tension to smooth the same upon the conformator; and to provide a flexible cosmetic carrier folded into compact form, and drawn out of the holder or conformator as and when required, and which carrier, as an article 50 of manufacture, can be manufactured and sold independently of the holder or applicator and delivered in the carton to be placed within the applicator or holder or casing.

With the above objects in view and others which 55 will be detailed during the course of this description, my invention consists in the parts, features, elements and combinations thereof hereinafter described and claimed.

In order that my invention may be clearly

understood, I have provided a drawing wherein three or more forms are shown, viz.:

Figure 1 is a cross-section at any intermediate point of Figure 2;

Figure 2 is a perspective view showing my device with the rouge holder and rouge strip in place, parts being broken away and in dotted lines to show details;

Figure 3 is a perspective view of another form of my invention wherein the structure is given a 10 different shape from that of Figures 1 and 2;

Figure 4 is a cross-section of Figure 3 at any intermediate point;

Figure 5 is a cross-section of that form of my invention which is shown in Figure 6, the section being taken at any intermediate point;

Figure 6 is a perspective view of the structure of Figure 5, the form being somewhat changed;

Figure 7 is a perspective view of a structure similar to Figures 3 and 4, but containing a rouge 20 holder wound in reel form;

Figure 8 is a cross-section of Figure 7 taken at any intermediate point; and

Figure 9 is a plan view showing the manner of folding the rouge-holding material and certain 25 details of construction thereof, certain parts being broken off to curtail the view.

In the drawing, and particularly referring to the form of Figures 1 and 2, the holder or casing is shown to consist of a receptacle 1 composed 30 of a geometrical figure, the top of which is open, and in which a carton 2 of rectangular form is disposed, the top of which is likewise open, but which is provided with a short member 3 or ledge which holds the folded paper in place and prevents 35 it from rising at its inner folds above the top of the open casing or the top of the carton. At each end of the casing, on the outside thereof, the latter is provided with a hinged cover 4 having a lip 5 at its front, end flanges 6, and a back flange 7. This flanged cover or member is hinged at 8 to the casing. This cover is adapted to close down upon and cover the carton, casing and folded paper rouge carrier within the carton 2. Pivoted to the end flanges 6 of the cover is a 45 bar 9 having end extensions 10, the pivotal point being at 11 close to the front of the cover. The bar 9 is provided centrally with a spring lip extension 12, which snaps over and against the back of the casing 1, as shown in Figures 1 and 2. The bar and lip extensions 9—12 swing around the front part of the casing 1, under the bottom thereof, and hold the cover 4 firmly in position by the lip engaging frictionally with the back-angle of the casing, as shown in Figures 1 and 2. The bar 9 is also a tension member for the folded paper 50 rouge carrier.

As seen in all the figures except Figures 7 and 8, the paper or rouge carrier is folded lengthwise upon itself, Figure 9, as at 13, to provide the 60

two longitudinal, semi-flaps *a*, and is provided with the notches in the doubled edges, as at *b*, for the cut-away portion of the upper edge *14* of the front wall of the casing *1*, Figures 1 and 2. 5 As shown in Figures 1 and 2, the rouge-holding paper is also provided with a cut-out portion *c* and a crease *d* extending approximately midway across the same, said cut-out portion having a lower regularly curved edge *e*, and an upper scalloped edge *f*, the opening outline representing the shape to be given the imprint of rouge carried by the inner surfaces *a* of the paper. The outline is that of the lower and upper lips of a human being, the scalloped upper edge giving the 10 conventional shape termed "Cupid's bow" and "rose bud". The rouge is applied to the flaps *a* at the opening or cut-out portions *c*. The carrier is folded on the crease lines *g* into compact form and placed in the carton or casing, and 15 when drawn out is again folded on the line *d*, over the casing, as shown in the figures.

Tension is applied to the rouge carrier by the bar *9*, the rouge carrier passing out of the casing over its top edge as at *15*, and drawn downwardly 20 tightly under bar *9*, as at *16*, where it is tightly clamped against the bottom of the casing. When the rouge is applied, the casing is turned bottom-up, as shown in Figure 2.

The casing shown in Figures 1 and 2 is also 25 provided with a rouge-holding space *17* in front of the carton *2*, this being due to the shape of the casing. This space may contain rouge in a certain form or face-powder in solid form.

Figures 3 and 4 show a form of my invention 30 which is rectangular or oblong; but, which in all other respects is substantially the same as the form of Figures 1 and 2, and in which the same reference characters are used. This form may also contain a carton or holder *2*, though 35 this is not essential in either form. The back flange *1* has been omitted from Figures 3 and 4, and in place thereof a hinge *8a* is made integral with the back of the casing, and this structure can, of course, be applied to the form of Figures 40 1 and 2. In this form (of Figures 3 and 4) the rouge-holding paper, Figure 9, is substantially the same as that of Figures 1 and 2 and is held under tension by the hinged bar *9*, which snaps by a flange *18* over one angle of the casing *1*, 45 at the junction of its back and bottom.

In both forms of Figures 1 to 4, when the rouge or coloring material is entirely used from a given opening *c*, the latch bar *9* is released, the rouged material is grasped by the thumb and 50 first finger, and drawn forcibly across the exposed edge of the bar *5*, the notches *b* facilitating the operation, which cuts off the material leaving a flap under the bar *5*, which is engaged by the thumb and fingers when it is desired to 55 draw out more rouged material.

In Figures 5 and 6, the casing is shown as diamond-shaped, as indicated at *20*, and is provided with a holding bar *21* hinged at *22* to the opposite ends of the casing, the holding bar 60 having the side members *23* and the tension clamping bar *24* at their forward ends to which a snap fastener lip *25* is applied which swings under the hinge *26* of the front member *27* of the casing *20*. The front member has formed in 65 continuity therewith a top member *28*, which two members constitute the open side of the casing *20*, and which swing upon the hinge *26* when it is desired to replace or adjust the rouged material. In this form of my invention, the rouge-carrier is differently folded. It is folded longi- 70

tudinally as at *13*, Figure 9, to produce the rouge-holding flaps *a*; but, is folded reversely at *d* to bring the rouge-holding portions *e* and *f* of the openings *c*, opposed to each other, and is also folded reversely at *g*, so as to nest the same within the casing *20*. The rouge is applied to the flaps *a*, at the openings *c*, of the paper in the same manner as in Figures 1 to 4. This form of my invention is very simple, in that the casing or holder is composed of the two integral members *20*, and the two integral hinged members *21* and *28*, the bars *21* and *24* operating to hold the hinged member firmly in contact with the fixed members *20*, and to hold the rouge-carrying material or paper under tension over the edges of the hinged portion. This form of my device does not have a carton or holder; but, the rouged material or paper fully protects the rouge, since the portions to which the rouge is applied are folded in upon each other so as to 20 protect the same.

In the form of my invention in Figures 7 and 8, I have shown a rectangular casing similar to Figures 5 and 6; but, in this form, I have shown the rouge-carrying material in the form of a 25 cylindrical reel. Otherwise, the form of the holder, which is rectangular, is composed of parts similar to Figures 5 and 6, and the same reference characters are applied to the corresponding parts. In this form of my invention, the reel of rouged material is indicated at *29*, and the end thereof is drawn out over the hinged members *28* and *27*, and placed under tension by the combined effort of bars *21* and *24*, which are held in position by the snap member *25*, which encircles a bead of the hinge *26*. The reel *29* is held in place by spool *30*, journaled in the casing *20*, on trunnions *31*, at opposite ends thereof. The rouge is applied to one surface of the paper, and the latter is rolled with the rouge outwardly. 40 Consequently, it comes out of the casing with its rouged surface outwardly and is bent over the angle of the hinged portion *27*—*28*, and is held under tension and clamped by the bar *24*.

From the foregoing description of the several 45 forms of my invention, it will be seen that the folded rouge-carrying material of Figure 9 is stacked in the casing *1* or in the carton *2* contained within the casing. An end is then drawn out over the free edge of the casing or carton 50 which has the ledge *3* thereon, the ledge serving to hold the rouged material or carrier within the carton or casing, and preventing it from springing out of the casing and thus unfolding. The free end is then drawn down over the body 55 of the casing and momentarily held while the bar *9* is engaged with the same, thus putting the paper under tension. In this condition the bar *9* is fastened by the clip *12*, which clamps the free end of the rouge-carrying material 60 against the body of the box. The rouged material is thus bent along the line *d* which is approximately midway of the opening *c* therein, so as to expose the rouge with which the paper has been supplied. The casing is then so manipulated 65 conveniently in either hand as to enable the lips to be compressed within and about the edges *e* and *f* of the opening *c*. This manipulation compresses the rouge-carrier upon the two lips of the user leaving an exact impression on 70 the upper and lower lips. When the rouge has been entirely used, or it is desired to draw out another unit of the folded material, the bar *9* is released, thus releasing the free end of the rouge-carrier which is drawn tightly against the 75

edge 14 under the lip 5 of the cover, enabling it to be removed from the strip. This leaves a short end *h* which the user grasps, enabling her to draw out the next succeeding unit of folded material which is in turn drawn around the edge 14 under lip 5 and across the lower left-hand angle of the casing, as seen in Figure 5, and then under the bar 9, at which point tension is applied and it is clamped firmly in position on the body of the casing. The same manipulation takes place in all the forms of my invention, save that of Figures 7 and 8, wherein the strip of rouge-carrying material is of single thickness, and is drawn out between the two hinged members of the body portion and laid around the angle of the parts 27 and 28, and clamped by the bar 24 against said member 27.

It will be observed that my device is wholly sanitary, the rouged material being contained within a casing or carton and entirely enclosed thereby. The rouge carrier is used only when required, and at that time may be drawn out and clamped in position as shown and described in the foregoing.

In all forms of my device, it will be seen that the cover 4 and the members 27 and 28 constituting a closure are firmly held closed and in position by swinging the latch member 9 or 24 around the body of the casing and snapping the same firmly in contact with the angle of the casing.

In the form of my device shown in Figure 7, I have illustrated a doubled series of units, the same as in Figure 9. This doubled strip, or series of units, is drawn from a reel, as in Figure 8, outwardly through the opening under the edge of the member 28, around the latter, and over the top of the member 27, tension being applied by the member 23—24. Thus the strip of units will be disposed on the casing of Figure 7 in the same manner as in the other figures, and the crease line *d* will arrange itself at the angle of the two members 27 and 28 and thus dispose the rouged paper so that the impression of the lips may be given as in the remaining figures.

In the form of my invention shown in Figure 8, the casing members 27 and 28 may be integral as shown; but, the member 24 may be extended in the form of a stencil and cut out to provide a pattern in the form of the human lips. Thus the strip of units would be reeled off outwardly around the edge of the member 28 under the stencil and around the member 27 between the same and the upper portion of the stencil, where it would be clamped by the member 24 of the stencil, as described with reference to the structure of Figure 8. In this way the outline of the human lips would be provided by a stencil while the rouged unit or strip of material would pass under the stencil and over the rigid members 27 and 28 of the casing. The tension would be applied in the same manner as with reference to the other figures, as by the bar member 24 of the stencil which would be clipped over the hinge 26 by the lip 25.

In the form of my invention shown in Figure 9, I have set forth a strip of folded or doubled material arranged in a series of units with the rouge applied thereto in continuity; but, I may employ a strip of material the same as in Figure 8 with the rouge applied thereto at spaced intervals in the form of the outline of the lips, this rouge outline being separated by plain portions of material. In this way I use the strip in reel form, as in Figure 8, and draw out the same from the

casing in the manner in which I have described the operation of Figures 1 to 7.

Having thus described my invention, what I claim and desire to secure by Letters Patent is:

1. A rouge holder consisting of flexible material folded lengthwise along its opposite edges, the fold of the material having rouge applied thereto at spaced intervals.

2. A rouge applicator rectangular in form, a hinged closure member secured thereto, and a spring latch or bar pivotally applied to the hinged closure member for holding rouged material in place and under tension on the outside of the applicator.

3. A rouge applicator consisting of two hinged portions forming a rectangular casing, and means comprising a hinged bar swinging freely relatively to the casing and snapped around an angle thereof.

4. A cosmetic applicator comprising a container and a rouged strip held therein, said container having a closure at one side thereof for retaining said strip, and an integral hinged clamping member formed in extension of said closure and engaging the rouged material held in the container.

5. A cosmetic applicator comprising a casing having a hinged cover, a carton contained within the casing, and having an open side under said cover, rouged folded material within the carton, means for leading the rouged material to the outside of the casing between the carton and cover, and means for holding the material smoothly and under tension on said casing.

6. A cosmetic applicator comprising a rectangular casing having a hinged cover, rouge-holding material applied about the casing, and a combined latch and tension bar for holding the cover firmly in position upon the casing and for holding the rouged material under tension about the casing.

7. A cosmetic holder comprising a casing having one side thereof open, a hinged cover secured to the casing at one side thereof, a bar hinged to the cover for holding said cover tightly upon the casing, and means for snapping the bar in position against the casing.

8. A rouge applicator consisting of a casing, a rouge holding strip contained within said casing, a bar pivoted to the outside of said casing adapted to swing about the same and having means for clamping the rouge holder to the outside of the casing.

9. A rouge holder consisting of a plurality of connected rouge-holding units, the units being separated by notches applied at opposite edges thereof, and the said units also being creased transversely of the units between the notches and also creased transversely of the units.

10. A rouge holder comprising a flexible strip of material folded lengthwise along its margins and having its edges in contact centrally of the strip, rouge applied to the said margins, means imposed upon the strip enabling it to be divided into units, crease-marks applied to the strip enabling it to be folded transversely, and apertures of predetermined shape formed in the body of the strip through which the lips may pass.

11. A rouge holder comprising a stack formed into spaced units each unit being folded at its opposite edges and provided with an opening, and said unit having rouge applied to its exposed surface showing through said opening.
